UNITED STATES PATENT OFFICE.

THOMAS H. SPARKS, OF WICHITA, KANSAS.

APPARATUS FOR RELIEVING TIRES FROM THE WEIGHT OF AUTOMOBILES.

1,114,407.

Specification of Letters Patent.

Patented Oct. 20, 1914.

Application filed April 8, 1914. Serial No. 830,403.

To all whom it may concern:

Be it known that I, THOMAS H. SPARKS, a citizen of the United States, residing at Wichita, in the county of Sedgwick and State of Kansas, have invented certain new and useful Improvements in Apparatus for Relieving Tires from the Weight of Automobiles; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in apparatus for relieving the tires from the weight of automobiles when the machine is in a garage or in storage and consists essentially in the provision of a tilting rack which sustains the weight of the automobile and in the provision of means whereby weight of the automobile, after passing up inclined tracks, is automatically transferred to a tilting rack, thus relieving the tires upon the wheels from the weight of the machine.

My invention comprises various other details of construction, combinations and arrangements of parts which will be herein-after fully described, shown in the accompanying drawings and then specifically defined in the appended claims.

I illustrate my invention in the accompanying drawings, in which:

Figure 1 is a side elevation of the apparatus. Fig. 2 is a top plan view. Fig. 3 is a central longitudinal sectional view. Fig. 4 is a front end elevation, and Fig. 5 is a detail perspective view of a part of the apparatus.

Reference now being had to the details of the drawings by letter, A designates the floor of the apparatus having cross beams B at one end and C intermediate the ends, preferably at the center of the flooring. Inclined tracks, designated by letter D, are supported at their inner ends upon the cross-piece C and their under edges are beveled as at D' where they rest upon the upper surface of said flooring. Other tracks E are connected by means of hinges F to the cross-piece C and are designed to tilt to the position shown in dotted lines in Fig. 1 of the drawings.

The rack comprises two sills G which are parallel to each other and which have cross-

pieces G' and intersecting braces G². Fas-
tened to the under side of each sill, prefer-
ably at its longitudinal center, are the con-
caved bearing plates H which are fulcrumed 60
upon the upper convexed edges I of the ad-
justable blocks I'. Adjustable bracket stand-
ards, designated by letters J and J', have
flanges J² which are slotted as at J³, said
flanges being adapted to rest upon the cross- 65
piece C. Bolts, designated by letter J⁴ pass
through the slots J³ and also holes formed in
the crosspiece C and are provided with nuts
upon the threaded ends and serve to hold
the two bracket standards in different rela- 70
tive adjustments upon said crosspiece. The
blocks I' are provided with elongated slots
I², as shown clearly in Fig. 3, and bolts K
pass through the slots I² and also through
apertures in the bracket standards J and are 75
provided with nuts upon their threaded ends
and afford means for holding the blocks I'
in place between the standards and above
the crosspiece C. Braces J⁶ are fastened at
their forward ends to the crosspiece B and 80
at their rear ends to the standards J.

Upon reference to Fig. 3 of the drawings,
it will be noted that the lower edges of the
blocks I' are inclined and wedges L rest upon
the upper surface of the crosspiece and their
upper inclined edges contact frictionally with
said inclined lower edge of the blocks I' and 85
afford means for holding the latter in dif-
ferent vertically adjusted positions, accord-
ingly as it may be desired to cause the rack 90
to tilt at different inclinations.

The means for adjusting the forward end
of the rack is clearly illustrated in Figs. 3
and 4, in which it will be noted that angled
posts N are provided with elongated slots 95
N' through which bolts N² pass and which
bolts also pass through the slots O formed in
the inclined braces O' which are fastened at
their lower ends to the crosspiece B and
their upper ends to the fixed posts B'. The 100
lower portions of the angled posts N have
perforations N³ and bolts N⁴ passed through
slots N⁵ in the crosspiece B and which pro-
vide for the lateral adjustment of said angle
posts, suitable nuts N⁶ being fixed to the 105
threaded ends of said bolts N⁴. An angle
bar M, having its angled portion corre-
sponding to and engaging over the angled
portion of the post N, is provided with
apertures M¹ and M² and a bolt Q passes 110
through an aperture in the angled posts and
also one of the perforations M¹ in the angled

bar M and the bolt N⁴, which passes through an aperture in the angled post M, also passes through an aperture or perforation M³ in the angle bar, the two bolts N⁴ and Q serving to hold said angle bar in different vertically adjusted positions to correspond with the vertical adjustment of the blocks I'. In order to guide the rack in its tilting movements, I provide bars R, bolted or otherwise fastened to the opposite sides of each sill of the rack and which, as the rack tilts, contact with the opposite edges of the angled posts N.

Referring to Fig. 4 of the drawings there will be seen a rock shaft S journaled in suitable bearings upon the fixed post B', and crank arms S' are fastened to the ends of said shaft S and carry pins S² upon which the eyes S³ and S⁴, formed respectively at the ends of the supporting rods S⁵ and S⁶, are journaled and which are held to the pins by means of the nuts S⁷. The corresponding rod S⁵ has an eye S⁸ at its lower end through which the rod S⁹ passes and the lower end of each supporting rod S⁶ passes through an aperture in the rod S⁹ and has a nut S¹⁰ fitted to its threaded end. Upon reference to Fig. 4, it will be noted that the supporting rod S⁵ engages a notch S¹¹ formed in the front end of the track, while the supporting rod S⁶ passes through an aperture S¹² formed in the track, which forms means for fastening the rod S⁹ to the tracks E. Upon reference to Figs. 1 and 4 of the drawings, it will be noted that the free ends of the tracks E project over and are supported by the rod S⁹. Projecting from the shaft S is a rod T, forming a crank handle whereby the shaft S may be rocked. The means co-operating with the crank handle T for raising and lowering the free ends of the tracks E consists of the bar P which is pivoted at P' to the horizontally disposed bar P² fastened to the crosspiece B, the upper end of the bar P having a bar P³ pivoted thereto which has a forked end P⁴, as shown clearly in Fig. 5 of the drawings, and is adapted to receive the crank arm T when the apparatus is actuated to cause the tracks E to drop down to the positions shown in dotted lines in Fig. 1. Said bar P² has a series of perforations P⁵ formed therein and the bar W is provided with perforations W' at its lower end to receive a pivotal bolt V, affording means whereby the two bars W and P may have relatively adjusted relations. In order to limit the swinging movement of the bar P in one direction, the plate X is fastened at its lower end to the bar P² and its free end, which is beveled, is positioned in the path of the lever P and against which the latter is adapted to contact. The upper end of the bar W is pivotally connected at W⁶ to a bar Y which is provided with perforations Y'

to receive the bolt Y², thus allowing for different adjusted positions intermediate the bars Y and P.

Referring to Fig. 5 of the drawings, a lever Z has forked arms Z' which are bent to form hooks and which engage over the rod S and which lever is provided for the purpose of rocking the rod S by the forked end of the lever engaging the crank arm T and throwing the same from its lowest position, shown in dotted lines, to the position in solid lines in Fig. 5. At corresponding ends of the sills are pivotally connected the bars G² having curved ends G³ which are adapted to rest upon the flooring when the rack is in a horizontal position and as shown in dotted lines in Fig. 1. When the bars G² are not in use, they are adapted to swing back and rest upon the pins G⁴.

The operation of my apparatus will be readily understood and is as follows: When the parts are in the position shown in Fig. 3, the car is driven up the inclined tracks to the positions assumed by the wheels in dotted lines. When the forward axle of the vehicle comes in contact with the bar W, the forked bar P² will push upon the crank handle T, causing the shaft S to rock and which in turn, through the medium of the crank arms S', will cause the two supporting rods S⁵ and S⁶ to lower with the forward ends of the tracks E to the positions shown in dotted lines in Fig. 1. Simultaneously with the dropping movement of the tracks E, the weight of the forward end of the vehicle will be transferred from the hinged tracks to the forward portions of the sill and the weight of the vehicle will then cause the rack to tilt and the leverage action of the rack in tilting, which rack at the left of its pivotal point at this time is in contact with the under edge of the rear axle of the vehicle, will cause the latter to be raised from the floor. When the parts assume the position shown in dotted lines in Fig. 1, the rack will be positioned in a horizontal position and all of the wheels of the vehicle will be relieved of the weight thereof and will be positioned out of contact with the hinged tracks and flooring, drawing the entire weight of the vehicle upon the rack. When it is desired to relieve the weight of the vehicle from the rack, the operator first swings the bar P³ to an upright position, after which the rod S may be rocked by swinging the lever Z, which in its upward movement will contact with the crank arm T and throwing the same toward an upright position and, through the medium of the connecting means intermediate the shaft S and the rod S⁹, the forward ends of the tracks E will be raised into contact with the forward wheels of the vehicle. A further rocking movement of the shaft S will cause the rack to tilt with the hinged tracks E until

the parts assume their normal positions, thus allowing the car to run by gravity down the tracks and off the flooring. After the car has left the apparatus, the bar P^3 is pushed down to the position shown in Fig. 3 of the drawings, in which its forked end is engaged by the crank arm T , thus resetting the apparatus.

By the adjustable means shown, the apparatus may be adjusted for different heights and widths of cars as will be readily understood.

What I claim to be new is:

1. An automobile rack for relieving the weight of the vehicle from the tires of the wheels, comprising inclined and hinged tracks, a rack, bearing members fastened thereto, laterally adjustable posts between which the sills of the rack are mounted, vertically adjustable means intermediate said posts for adjusting the height of the rack, slotted blocks intermediate said posts and wedges underneath the slotted blocks, the upper ends of said blocks being convexed and adapted to engage the bearing members upon the sills of the rack, bolts passing through the slots in said blocks and said posts, and automatically-operated means actuated by contact of the forward end of the car therewith for causing the hinged tracks to lower as the rack tilts, thereby throwing the weight of the vehicle upon said rack.

2. An automobile rack for relieving the weight of the vehicle from the tires of the wheels, comprising inclined and hinged tracks, a rack, bearing members fastened thereto, laterally adjustable posts between which the sills of the rack are mounted, vertically adjustable means intermediate said posts for adjusting the height of the rack, slotted blocks intermediate said posts and wedges underneath the slotted blocks, the upper ends of said blocks being convexed and adapted to engage the bearing members upon the sills of the rack, bolts passing through the slots in said blocks and said posts, a vertically adjustable angle bar against which the forward end of the sills of the rack are adapted to contact, and automatically-operated means actuated by contact of the forward end of the car therewith for causing the hinged tracks to lower as the rack tilts, thereby throwing the weight of the vehicle upon said rack.

3. An automobile rack for relieving the weight of the vehicle from the tires of the wheels, comprising a flooring with cross-pieces thereon, slotted blocks with their lower edges inclined, wedges upon a cross-piece of the flooring upon which said blocks are supported, the upper edge of said blocks being convexed, fixed inclined and hinged tracks, a tilting rack having sills, bearing members fastened to the latter and adapted

to rest upon said convexed ends of the blocks, laterally adjustable posts intermediate said blocks, fixed posts upon one of said crosspieces at the end of the flooring, laterally and vertically adjustable angle posts, an adjustable angle bar upon each of said angle posts, and automatically-operated means actuated by contact of the forward end of the car therewith for causing the hinged tracks to lower as the rack tilts, thereby throwing the weight of the vehicle upon said rack.

4. An automobile rack for relieving the weight of the vehicle from the tires of the wheels, comprising a flooring with cross-pieces thereon, slotted blocks with their lower edges inclined, wedges upon a cross-piece of the flooring upon which said blocks are supported, the upper edge of said blocks being convexed, fixed inclined and hinged tracks, a tilting rack having sills, bearing members fastened to the latter and adapted to rest upon said convexed ends of the blocks, laterally adjustable posts intermediate said blocks, fixed posts upon one of said crosspieces at the end of the flooring, laterally and vertically adjustable angle posts, an adjustable angle bar upon each of said angle posts, a bar secured to the crosspiece at one end of the flooring, a pivotal bar against which the vehicle is adapted to contact as it moves up the track of the apparatus, a rock shaft and means for rocking the same as the car contacts with said pivotal bar, supporting bars connected to said crank shaft, a rod connected to said supporting bars and engaging the forward ends of said hinged tracks.

5. An automobile rack for relieving the weight of the vehicle from the tires of the wheels, comprising a flooring with cross-pieces thereon, slotted blocks with their lower edges inclined, wedges upon a cross-piece of the flooring upon which said blocks are supported, the upper edge of said blocks being convexed, fixed inclined and hinged tracks, a tilting rack having sills, bearing members fastened to the latter and adapted to rest upon said convexed ends of the blocks, laterally adjustable posts intermediate said blocks, fixed posts upon one of said cross-pieces at the end of the flooring, laterally and vertically adjustable angle posts, an adjustable angle bar upon each of said angle posts, a fixed bar fastened to the crosspiece at one end of the flooring, upright bars pivotally connected to said fixed bar and having adjustable pivotal link connections, a forked bar pivoted to one of said upright bars, a rock shaft having a crank arm adapted to be engaged by said forked bar, cranks upon the rock shaft, supporting bars pivotally connected to the crank arms, and a rod connected to the supporting rods and to the forward ends of the hinged tracks.

6. An automobile rack for relieving the

weight of the vehicle from the tires of the wheels, comprising a flooring with cross-pieces thereon, slotted blocks with their lower edges inclined, wedges upon a cross-piece of the flooring upon which said blocks are supported, the upper edge of said blocks being convexed, fixed inclined and hinged tracks, a tilting rack having sills, bearing members fastened to the latter and adapted to rest upon said convexed ends of the blocks, laterally adjustable posts intermediate said blocks, fixed posts upon one of said crosspieces at the end of the flooring, laterally and vertically adjustable angle posts, an adjustable angle bar upon each of said angle posts, a fixed bar fastened to the crosspiece at one end of the flooring, upright bars pivotally connected to said fixed bar and hav-

ing adjustable pivotal link connections, a forked bar pivoted to one of said upright bars, a rock shaft having a crank arm adapted to be engaged by said forked bar, cranks upon the rock shaft, supporting bars pivotally connected to the crank arms, a rod connected to the supporting rods and to the forward ends of the hinged tracks, a forked lever having arms which are bent into hooks and engaging said rock shaft and forming means to return the shaft to its normal position by contact with the crank arm. 20 25 30

In testimony whereof I hereunto affix my signature in presence of two witnesses.
